UNITED STATES PATENT OFFICE.

NATHAN M. LOWER AND ALBERT R. CHALKER, OF PITTSBURGH, PENNSYLVANIA,
ASSIGNORS TO LOCOMOTIVE STOKER COMPANY, A CORPORATION OF PENNSYLVANIA.

DISTRIBUTOR FOR STOKERS.

Original application filed March 13, 1922, Serial No. 543,329. Divided and this application filed April 7, 1923. Serial No. 630,639.

To all whom it may concern:

Be it known that we, NATHAN M. LOWER and ALBERT R. CHALKER, citizens of the United States, and residents of Pittsburgh, county of Allegheny, and State of Pennsylvania, have invented certain new and useful Improvements in Distributors for Stokers, of which the following is a specification, and which are illustrated in the accompanying drawings, forming a part thereof.

This invention relates to distributor tubes or nozzles through which coal is discharged into a fire box of a boiler, and while it is intended to be employed in connection with stokers of various types or designs it is particularly adapted for use on, and for simplicity of illustration is shown as being connected with, a stoker mechanism of the type forming the subject-matter of Letters Patent No. 1,371,252 granted to Nathan M. Lower on March the 15th, 1921. This invention relates to the general type of distributors disclosed in our co-pending application S. N. 543,329 filed March 13, 1922, of which this is a division.

As the invention appertains primarily to the distributor, only so much of the remainder of the stoker mechanism is shown as is necessary to indicate the relation of the parts. In stokers of this type, portions thereof extend into the fire box and being subjected to the intense heat therein are rapidly destroyed and must therefore be frequently replaced.

One of the objects of this invention is to provide a construction in which the parts of the distributor which are in danger of being burned off are removable, thus reducing the cost of replacement.

A further object of the invention is to provide means for cooling the exposed parts and thus lengthening their term of service; and a still further object is to provide an improved form of baffle or abutment which not only arrests a portion of the impelled fuel and delivers it to the back end of the fire box, but also cooperates with the deflector plate to evenly distribute the coal over all portions of the grates.

Other and further objects and advantages of the invention will appear from the description, taken in connection with the accompanying drawings, in which—

Fig. 1 is a detail vertical section through

the back head of the locomotive fire box 55 showing the improved distributor applied thereto, a fragment of the adjacent portions of the stoker mechanism being shown in elevation;

Fig. 2 is a central, longitudinal, vertical 60 section of the distributor;

Fig. 3 is a bottom plan view thereof; and

Fig. 4 is a vertical section on line 4—4 of Fig. 1, looking in the direction of the arrows.

The stokers for use with which the improved distributor is especially adapted have heretofore been used in connection with locomotives, although it is understood that their use is not limited thereto. There is shown at 10 a portion of the back head of a boiler having an aperture in which is fitted a sleeve 11. A fragment of the stoker head is shown at 12, which in practice is known as the stoker elbow. The distributor member or tube 13, which may be of any suitable shape in cross-section, is fitted to the stoker elbow 12 and is secured thereto by means of a hook bolt 14. The bottom wall of the distributor member or tube is 80 continuous with the side walls thereof, and the parts are so arranged that the distributor tube projects into the sleeve 11.

The inner end of the tube 13 terminates substantially in the plane of the inner face 85 of the back head 10 and consequently the same is protected more or less from the intense heat of the fire box. A deflector plate 15 projects forwardly over the top of the tube and is removably secured thereto. Any 90 suitable means may be provided for detachably connecting the deflector plate to the tube. As shown, the deflector plate is provided with a stem 16 having a socket for fitting upon an upwardly projecting lug 17 95 on the top of the tube, the inner end of the stem 16 engaging under a lip 18 formed on the tube.

Suitable means are provided for causing a portion of the impelled fuel to be distributed over the rear part of the grates. In the embodiment selected to illustrate the invention, a suitable fuel directing member 24, is employed. This member takes the form of a cross bar presenting an upright face to the advancing fuel and may be termed a baffle or abutment. It is provided with a stem 23 by means of which it may be detachably

secured to the tube 13. Means are provided for detachably connecting the stem to the distributor tube 13. Any suitable attaching means may be used. As shown in Fig. 3 the 5 stem 25 is provided with laterally extending lugs 26, 27, which are adapted to engage keepers 28 and 29 rigidly secured to the bottom wall of the tube 13. The rear end of the stem 25 is provided with laterally extending shoulders 30 and 31, which are adapted to engage between the downwardly projecting lugs 32 and 33 rigidly secured to the bottom wall of the tube 13, and which are adapted to prevent the longitudinal 10 movement of the stem 25.

The stem 25 and the baffle plate 24 are cored to form a continuous passage therethrough, as indicated at 34 and 35. The passage 35 extends longitudinally through 15 the baffle plate and is open at the ends thereof.

At 36 there is shown the usual nipple extending through the floor of the elbow 12 and having a series of jet openings 37 directed through the tube, the nipple 36 being adapted for the attachment thereto at its lower end of a steam pipe 38. A pipe or 20 nipple 39 leads laterally from the nipple 36 below its jet openings and terminates adjacent to the rear end of the passage 34 through the stem 25 into which it discharges. The rear end of the stem 25 is flared as indicated at 40 to permit the entry of air induced by the steam blast from the nipple 39 25 to thereby not only assist in cooling the baffle plate or abutment and its supporting stem but also to assist in distributing the fuel over the fire.

In order to permit the pipe 39 to extend 40 well into the passage 34 and yet provide for the assembling of the parts, the upper wall of the stem 25 may be slotted at its rearward end as indicated at 41.

In the operation of the device the fuel is 45 discharged into the tube 13 from the elbow 12 and is projected forwardly through the tube by the steam issuing from the jet openings 37 and scattered through the tube, some of it being thrown upwardly against the plate 15 which deflects it downwardly and scatters it over the central zone of the fire box, the plate 15 preventing the fuel from 50 being thrown upwardly and into the boiler tubes; some of the fuel strikes the side walls 55 of the tube and is thereby prevented from being too widely scattered; some of it will encounter the blasts of air and steam through the opening or passage 35 and will be directed to the sides of the fire box, while 60 some of it is projected forwardly through the tube without encountering any of its walls and is carried well to the front end of the fire box. The lower stratum of the fuel follows the bottom of the tube and 65 encounters the upstanding baffle plate or abut-

ment 24, is arrested and dropped upon the rearward end of the grate. Lumps of coal in the lower stratum which strike the abutment or baffle plate 24 below their centers of gravity, bound over the abutment and 70 fall upon the grate a little in front of it.

When under the influence of the intense heat of the furnace the baffle plate or abutment, or its stem, or the deflector plate becomes burned away or warped, they may be 75 readily replaced by detaching the same from the tube 13. This detachability of the parts not only reduces the cost of replacement but permits the interchange of parts with the minimum expenditure of labor and since the 80 parts may be replaced without the necessity of waiting for the entire cooling of the firebox, a saving of time in making the change is also effected.

It is thought from the foregoing taken 85 in connection with the accompanying drawings that the construction and operation of our device will be apparent to those skilled in the art, and that various changes in size, shape, proportion and details of construction 90 may be made without departing from the spirit and scope of the appended claims.

We claim as our invention:

1. A fuel distributor, comprising a tubular member having a continuous bottom wall, 95 an abutment member located beyond such bottom wall and having its longitudinal axis extending transversely to the axis of said tubular member, said abutment extending above the plane of the bottom wall of 100 said tubular member supporting means therefor, and means for detachably securing said supporting means to said tubular member.

2. In combination, a distributor tube for 105 stokers, an abutment extending transversely to the longitudinal axis of said tube and spaced therefrom and rising above the plane of the bottom thereof, and means for detachably securing the abutment to the tube. 110

3. In combination, a distributor tube for stokers, an abutment extending transversely to the longitudinal axis of said tube and rising above the plane of the bottom thereof, and means for detachably securing the abutment to the tube, such abutment and attaching means having a continuous passage 115 therethrough, and a pipe discharging into the rearward end of the passage.

4. In combination with a distributor tube for stokers, a T-shaped member, the stem of which is detachably secured to the bottom of the tube and projects beyond the end thereof, and the cross element of which projects above the level of the tube bottom and forms an abutment for fuel issuing from the tube. 120 125
